Cincinnati, OhioCLAIM[] Term: 14 Years

The ornamental design for an embossed pattern for a non-woven wipe, as shown and described.

[21] Appl. No.: 29/073,522*DESCRIPTION[22] Filed: Jul. 14, 1997

The sole figure is a top plan view of an embossed pattern for a nonwoven wipe showing our new design. The broken line shown in the figure defines the boundaries of the embossed paper product in which the pattern is embodied, as well as one repeat unit of the claimed design. The broken lines form no part of the claimed design.
